UNITED STATES PATENT OFFICE

2,497,502

RAILROAD SWITCH ADJUSTMENT

Albert F. Huber, Chicago, Ill., assignor to American Brake Shoe Company, New York, N. Y., a corporation of Delaware

Application February 24, 1945, Serial No. 579,518

21 Claims. (Cl. 246—450)

1

The invention relates to railroad switches and more particularly to devices for adjusting such switches.

It is an object of the invention to provide a simple and reliable adjusting mechanism whereby both the distance between switchpoints and the usual lost motion connection with the switch throwing mechanism may be conveniently adjusted.

According to a preferred form of the invention, a pair of housing members connects the parts of a jointed switch rod. The housing members have suitable recesses or seats cooperating with a channel splice bar and the vertically disposed flat switch rod members are suitably clamped between. The housing members have suitable longitudinal recesses with threaded portions and guide portions to receive a sleeve nut for adjusting the length of the switch rod. Extending through aligned passages in the housings and in the sleeve nut is the operating rod which extends to the switch-operative device. The operating rod has suitable adjustment nuts fitting into recesses in the housings. A combined weather-protecting and locking cover surrounds tubular extensions on the housings and a hex portion on the sleeve nut to protect and lock the latter against turning.

The invention also consists in certain new and original features of construction and combinations of parts hereinafter set forth and claimed.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawings forming a part hereof, in which:

Fig. 1 represents a conventional type of switch with a switch adjustment according to the invention applied thereto;

Fig. 2 is a longitudinal plan section through the adjusting device;

Fig. 3 is a transverse section on the line 3—3 of Fig. 2;

Fig. 4 is a section on the line 4—4 of Fig. 2 illustrating the keyhole seat arrangement for seating the bolts in the housing;

Fig. 5 is a detail of one of the housings; and

Fig. 6 is a section taken on the line 6—6 of Fig. 2.

In the following description and in the claims, 55 an additional connecting rod 19 may be con-

2

various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and more particularly to Fig. 1, the conventional switch construction used for purposes of illustration comprises stock rails 10 and 11 and switchpoints 12 and 13, these rails resting upon conventional railroad ties 15; tie plates and spikes are omitted for simplicity of illustration. The stock rails 10 and 11 are of standard T-section and the switchpoints 12 and 13 may also be of standard T-section. The rails 10 and 13 may be main line rails and the rails 11 and 12 may be turn-out or branch line rails.

The switchpoints 12 and 13 are connected by switch rods 16 and 17, two being shown for purposes of illustration, although any suitable number may be used.

30 The switch rods 16 and 17 are made up of the usual flat bar steel with their wider or flat surfaces disposed vertically and their narrower or edge surfaces disposed horizontally. Such switch rods are sometimes referred to as "vertical" switch rods or as disposed "edgewise." Each rod is made in two sections, the sections of rod 16 being connected by the adjusting device 24 and the sections of rod 17 being connected by the adjusting device 25.

40 The vertically disposed switch rods 16 and 17 are connected to their switchpoints 12 and 13 by suitable swivel connections indicated by 22 and 23, described and claimed in Mock Patent No. 2,213,500, dated September 3, 1940. As explained in the patent, these swivel connections include dogs 74 and clips 75 which provide swivel movement about vertical axes between the switch rods and the switchpoints.

For operating the switch, an operating rod 18 is connected to the adjusting device 24, as indicated. The operating rod 18 may extend to any suitable hand or power-driven switch-operating device (not shown), such as a conventional hand switchstand or interlocking machine. If desired,

nected to the other adjusting device 25, extending to a locking device (not shown). In addition, a further rod 20 may be connected to switch-point 13 to operate signal control apparatus (not shown).

It will be understood that, if desired, the second adjusting device 25 may be omitted and any construction used in its place which would permit adjustment of the first adjusting device 24 hereinafter described more in detail. Also the 10 adjusting devices 24 and 25 may be used with other types of switch rods including so-called horizontal rods where the flat bar stock is disposed horizontally instead of vertically, and with other types of switchpoint connections.

Since the adjusting devices 24 and 25 are identical in construction (although they may be adjusted differently), it will be sufficient to describe in detail only the adjustment 24 which is connected to the switch-operating mechanism. This adjusting device comprises in general a pair of housing or anchor members 29 and 30 connected to the switch rod sections 26 and 27 and to a channel splice bar 28 by nut and bolt assemblies, indicated in general by 31 and 32. The two housings 29 and 30 are adjustably connected together by a sleeve nut 33, suitable clearance being provided in the bolt holes 65 through which the bolts 58 pass to permit adjustment of the distance between the housings 29 and 30, and thus the length of the switch rod 16. The operating rod 18 passes through aligned openings in the housings 29, 30 and in sleeve nut 33, and has suitable adjustment and lock nuts 36, 37, 45 for providing the proper degree of lost motion between the operating rod 18 and the adjusting device 24.

The housings 29 and 30 are of similar construction, the main difference being in the screw threads 38 and 73 which are of opposite hand. Housing 29 has a longitudinal channel running therethrough, part of which is provided with screw threads 38 and an adjacent part with a cylindrical bearing portion 39. Parts 38 and 39 cooperate with the sleeve nut 33 which has corresponding threaded and cylindrical portions for a purpose hereinafter described more in detail.

Housing 29 is provided with an inner clearance space 40 and an outer clearance space 41 surrounded by projecting tubular portion 46 ending in a flange bead 47. Outer recess 41 seats a tubular adjustment nut 36 having a rounded nose 42 cooperating with a corresponding rounded seat on the housing 29. Adjustment nut 36 also has clearance spaces 43 and 44 on opposite sides of a threaded portion 48 which cooperates with the screw threaded operating rod 18. Hex jamb nut 45 seats against adjustment nut 36 whose outer end has an outer hexagonal surface 48'.

The sleeve nut 33 has oppositely threaded ends cooperating with the oppositely threaded portions 38 and 73 on housings 29 and 30 to provide a turnbuckle effect so that, when a wrench is applied to the hex portion 50, the housings 29 and 30 will either be drawn together or spread apart. A split sleeve nut cover 51 comprising an upper half and a lower half has an internal hex wall 52 engaging the external hex 50 on the sleeve nut 33. Bolts 53 tightly clamp the cover 51 around the beaded sealing flanges 54 on housings 29, 30 to both seal the parts against the weather and to prevent turning of the sleeve nut 33.

The flanges 54 have arcuate notches 76 in which fit lugs 77 projecting from the inside surface of the halves of nut cover 51, which limit to 60 degrees the distance through which the nut cover 51

(and hex surface 50) can turn after assembly. The circumferential extent of the notches 76 corresponds to the normal 60 degree relationship of the hex surfaces and is necessary to insure registration of lugs 77 and notches 76, regardless of the particular adjusted rotative position of the sleeve nut 33. This makes it unnecessary to adjust sleeve nut 33 to some exact angle to permit fitting of the internal hex surface 52 of the nut cover 51 on the external hex surface 50 on the sleeve nut 33. The lugs 77 extend axially from inturned edges 78 of cover 51 to the internal hex surface 52 to take care of the different axial spacing of the housings 29, 30. The threads 38, 73 are sufficiently fine so that the limited 60 degree movement of the turnbuckle nut 33 causes no substantial change in the adjustment of the switchpoints.

Each housing 29 or 30 (Figs. 3-5) is provided with a keyhole slot arrangement having outer recess 55, an undercut space 56 and a recessed flange 57 for seating bolts 53 whose shanks fit the curved recesses of flanges 57 and whose heads 59 seat thereunder. A keeper 61 having curved recesses snugly fits against the shanks 58 to hold the bolts apart.

In insulating plate 62 with side flanges 69 and end flange 70 seats in the external recess 55 and insulating sleeve 63 surround the bolt shanks 58. 30 An outer insulating plate 64 with side flanges 71 and end flange 80 rests on the rod member 26 and the channel splice bar 28 seats over the insulation plate 64 (Fig. 3). The splice bar 28 is provided with clearance bolt holes 65 to permit adjusting, 35 as explained hereinafter. Splice plate 66 seats over the channel bar 28 and suitable nuts and lock washers 72 of the nut and bolt assemblies 31 firmly clamp the parts together.

Thus it will be seen, particularly from Fig. 3, 40 that the switch rod member 26 seats between the channel splice bar 28 and the housing 29 and is retained therein by side flanges 67 and 68 on these members with the electric insulating members 64 and 62 interposed. The switch rod members 26, 27 are electrically insulated from both channel bar 28 and housings 29, 30.

If desired, the second adjusting device 25 which connects with the lock rod 19 may be of smaller size than adjusting device 24 but retain the main features thereof.

Thus combined adjustment is provided for both adjusting the distance between switchpoints (or throw of the switch) and also the lost motion between switch operating mechanism and the switch. The device also suitably electrically insulates one switchpoint from the other.

It will be understood that for signal purposes it is very desirable to maintain an exact throw of the track switch. This is difficult to obtain even in new installations with non-adjustable switch rods because of inaccuracies, due to manufacture, in the rod, dog and clip lengths, in the planing of the switchpoints and incorrect positions of the stock rails. Since switch operating 60 mechanism often have throws greater than the switch throw, it is necessary to provide a lost motion connection between the standard switch operating rod 18 and the switch. The invention handles both of these adjustments simply and 65 reliably.

It is thought that the manner of using this invention will be apparent to those skilled in the art from the above description. Briefly, in order to adjust switch throw (length of switch rod 16), 70 it is necessary only to slacken off on the main

switch splice nut and bolt assemblies 31 and 32, remove sleeve nut cover 51 and turn adjusting sleeve nut 33 until the proper distance between switchpoints 12, 13 is obtained. It will be understood that the clearance holes 65 in the channel splice bar 24 permits this adjustment. As illustrated in Fig. 2, the switch rod 16 is shown adjusted substantially to its maximum length. After the adjustment of length of switch rod 16 it is only necessary to replace sleeve nut cover 51 and tighten the main splice bolts 31 and 32. Of course, when a plurality of switch rods are used, similar adjustments must be made simultaneously with the adjustment just described.

To adjust lost motion with respect to operating rod 18, it is only necessary to slacken off on the jamb nuts 45 and adjust the adjustment nuts 36, 37 at either or both ends to set the switch properly up against its stock rail at each extreme position. The jamb nuts 45 are then tightened. The adjustment of lock rod 19 on adjusting device 25 is similar to that of operating rod 18 on adjusting device 24 except that adjustment nuts 36, 37 will be adjusted tightly against the housings 29, 30 because the lock rod should have the same movement as the switch.

Thus a simple and convenient unitary adjustment is made possible both for switch throw and lost motion connection. The device suitably electrically insulates the switchpoints. The parts are rugged in construction, are not likely to get out of order and can be conveniently adjusted. The parts are also protected against the weather.

The close sliding fit at the cylindrical portions 39 between the sleeve nut 33 and the housings 29, 30 strengthens the assembly, lessens the tendency to bend and reduces wearing of the screw threads. The channeling of the housings 29 and 30 and of the channel splice bar 28 provides recesses for the tops, bottoms, sides and ends of the switch rod members 26 and 27 thereby relieving the splice bolts of assemblies 31 and 32 from shear. This bolt and splice bar construction also relieves stresses on the turnbuckle adjustment.

The use of the sleeve nut cover 51 and the outer projecting flanges 46 on the housings locks the turnbuckle sleeve nut 33 and also assists in protecting the parts from the weather. The use of vertical or edgewise switch rods and the horizontal relationship between the operating rod adjustment and switch rod adjustment places all adjusting nuts in position easily accessible to adjusting tool and for inspection.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a railroad switch rod adjustment, a pair of switch rod members, a connecting assembly comprising a pair of housing members, a splice bar, said housing members, switch rod members and splice bar having openings, bolts passing through said openings, for connecting respective housing and switch rod members to said splice bar, a sleeve having threaded connection with said housing members to provide turnbuckle adjustment for adjusting the length of the switch rod, a connecting rod passing through aligned openings in said housing members and said sleeve, said connecting rod having adjustment nuts for adjusting the connecting rod with respect to said connecting assembly, the openings in said splice

bar providing clearance to permit said turnbuckle adjustment.

2. In a railroad switch adjustment, a pair of switch rod members, a pair of housing members connected respectively to said switch rod members, said housing members each having an internally threaded longitudinal passage, an externally threaded turnbuckle sleeve having threaded engagement with said passages to adjust the distance between said housing members, a connecting rod passing through the aligned passages in said housing members and turnbuckle sleeve, and adjustment nuts threaded on said connecting rod.

3. In a railroad switch rod adjustment, a pair of switch rod members of oblong cross section, said rod members being disposed horizontally with their narrower sides directed upwardly, a channel splice bar having clearance holes, a pair of housings, said housings and said channel bar having oppositely disposed channel recesses for the respective switch rod members, each said housing having seats for receiving bolt shanks and undercut portions for receiving bolt heads, a keeper between the bolt shanks for holding the bolts in their respective seats, said bolts passing through said switch rod members and through said clearance holes in the channel splice bar, said bolts holding the aforesaid members in clamped relationship, and additional means for adjusting the distance between said housings, said clearance holes being of greater dimension than the shanks of said bolts to permit said adjustment.

35 4. In a railroad switch adjustment, a pair of switch rod members, a connecting assembly comprising a pair of housing members connected respectively to said switch rod members, a splice bar connecting said rod members, adjusting means to adjust the distance between said housing members, bolts passing through said rod and housing members and through said bar and having clearance with said bar to permit adjustment of said housing members when said bolts are loosened, and a connecting rod adjustably connected to said assembly.

5. In a railroad switch adjustment, a pair of switch rod members, a pair of housing members connected respectively to said switch rod members, a splice bar connecting said rod members, said housing members and said splice bar having opposed channel recesses to house said rod members, said housing members having aligned openings, a turnbuckle having threaded engagement with said openings to adjust the distance between said housing members, bolts connecting the respective housing and rod members to said splice bar and having clearance with said splice bar to permit adjustment of said rod members when said bolts are loosened.

6. In a railroad rod adjustment, a pair of rod members, a pair of housing members connected respectively to said rod members, said housing members each having a longitudinal passage, a turnbuckle to adjust the distance between said housing members, said housing members each having a threaded portion and a cylindrical bearing portion fitting corresponding portions on said turnbuckle.

7. In a railroad rod adjustment, a pair of rod members, a pair of housing members connected respectively to said rod members, said housing members each having an internally threaded longitudinal passage, an externally threaded 75 turnbuckle sleeve having threaded engagement

with said passages to adjust distance between said housing members, a connecting rod passing through the aligned passages in said housing members and said sleeve, the outer ends of said housing members having large recesses, adjustment nuts threaded on said connecting rod and seating in said recesses.

8. In a railroad rod adjustment, a pair of rod members, a pair of housing members connected respectively to said rod members, said housing members each having a longitudinal passage, a turnbuckle sleeve having threaded engagement with said passages to adjust distance between said housing members, said housing members each having a threaded portion and a cylindrical bearing portion fitting corresponding portions on said turnbuckle sleeve, an operating rod passing through the aligned passages in said housings and said sleeve, the outer ends of said housing members having large recesses, adjustment nuts threaded on said operating rod and seating in said recesses, and jamb nuts outside of said adjustment nuts.

9. In a railroad track rod adjustment, rod sections, a pair of adjustment housings one connected to each rod section, said housings having aligned openings, said openings each having a screw threaded portion, a turnbuckle having threaded portions for providing turnbuckle adjustment between said housings, said turnbuckle having a hex portion, said housings having aligned cylindrical portions, and a sleeve telescoping said cylindrical portions and having an internal hex surface fitting said turnbuckle hex portion.

10. In a railroad track rod adjustment, rod sections, a channel bar partially surrounding said sections, a pair of adjustment housings one for each rod section, bolts connecting said housings and rod sections to said channel bar, said housings having aligned openings, said openings each having an internally screw threaded portion and a guide portion, a sleeve having corresponding guide portions and externally threaded portions engaging said internally threaded portions for providing turnbuckle adjustment between said housings, said bolt-connected parts having clearance openings around said bolts to permit such adjustment, a connecting rod passing through said aligned openings, said connecting rod having adjustment nuts, said housings having cylindrical clearance recesses for said adjustment nuts, said sleeve having a central flat sided portion, said housing having aligned flanged portions and a split sleeve surrounding said flange portions and having an internal flat surface fitting said sleeve flat sided portion.

11. In a railroad track rod adjustment, vertically disposed flat rod sections, a vertically disposed channel bar partially surrounding said sections, a pair of adjustment housings one for each rod section, horizontal bolts connecting said housings and rod sections to said channel bar, said housings having aligned openings, said openings each having a screw threaded portion and a guide portion, a sleeve having corresponding guide portions and threaded portions for providing turnbuckle adjustment between said housings, said channel splice bar having clearance openings around said bolts to permit such adjustment, an operating rod passing through said aligned openings, said operating rod having adjustment nuts with rounded noses, said housings having cylindrical clearance recesses for said adjustment nuts, and jamb nuts outside of said adjustment nuts.

said sleeve having a central hex portion, said housings having aligned flanged portions, a split sleeve surrounding said flange portions and having an internal hex surface fitting said sleeve hex portion.

12. In a railroad track rod, a housing having an open face recess, the bottom of said recess having a depression with laterally projecting flanges having seats, bolts having their shanks in said seats and their heads under said flanges, a keeper positioned against said bolts, a rod section in said recess and having openings through which said bolts pass, and nuts on said bolts to hold said rod section and housing together.

13. In a railroad track rod adjustment, a pair of track rod members, a connecting assembly comprising a splice bar on one side of said track rod members and an adjustable device on the other side of said track rod members, said adjustable device comprising a pair of anchor members with an adjustable member connecting said anchor members to adjust the distance between said anchor members, bolts clamping the respective anchor and track rod members to said splice bar, and electric insulation disposed between said track rod members and said connecting assembly.

14. In a railroad track rod adjustment, a pair of track rod members, a connecting assembly comprising a splice bar on one side of said track rod members and an adjustable device on the other side of said track rod members, said adjustable device comprising a pair of anchor members with an adjustable member connecting said anchor members to adjust the distance between said anchor members, bolts clamping the respective anchor and track rod members to said splice bar.

15. In a railroad track rod adjustment, rod sections, a pair of adjustment housings one connected to each rod section, said housings having aligned openings, said openings each having a screw threaded portion, a turnbuckle having threaded portions for providing turnbuckle adjustment between said housing, said turnbuckle having a polygonal wrench-engaging portion, said housings having aligned cylindrical portions, and a sleeve telescoping said cylindrical portions and having an internal polygonal surface fitting said turnbuckle polygonal portion, said sleeve and housing having interfitting lug and recess engagement permitting limited turning of said sleeve with respect to said cylindrical portions through an angle corresponding to the angle between the surfaces of said polygonal portion.

16. In a railroad switch adjustment, a set of switch rails, a switch rod comprising a set of switch rod members connecting said rails, each set of switch rod members having a longitudinal opening, a connecting assembly including said longitudinal openings, an externally threaded, rotatable adjusting sleeve disposed in said openings and having screw threaded engagement with at least one of said openings to adjust switch rod length, a connecting rod passing through said adjusting sleeve axially thereof, and adjustable elements acting between said connecting rod and said assembly.

17. In a railroad switch adjustment, a pair of switch rod members connectable to the switch-points, a connecting assembly comprising a pair of anchor members connected respectively to said switch rod members, a splice bar connecting said rod members, said rod members, anchor members and splice bar having aligned openings, bolts passing through said aligned openings to connect

corresponding anchor and switch rod members to said splice bar and having clearance with said splice bar to permit adjustment of said anchor members and rod members with respect to said splice bar when said bolts are loosened, and adjusting means to adjust the distance between said anchor members.

18. In a railroad switch adjustment, switch-points, a switch rod connecting said points and comprising a pair of comparatively flat rod members disposed with their narrower sides facing upwardly, a threaded adjustable device connecting said rod members to adjust the distance between said rod members, a splice bar, said rod members and splice bar having aligned openings, horizontally extending bolts passing through said aligned openings for clamping the respective rod members to said splice bar.

19. In a railroad switch adjustment, switch-points, a switch rod connecting said points and comprising a pair of comparatively flat rod members disposed with their narrower sides facing upwardly, a threaded adjustable device connecting said rod members to adjust the distance between said rod members, a splice bar, said rod members and splice bar having aligned openings, horizontally extending bolts passing through said aligned openings for clamping the respective rod members to said splice bar, said splice bar and adjustable device having opposed shallow channel recesses to house said rod members, certain of said openings having greater dimensions than the shanks of said bolts to permit said adjustment.

20. In a railroad switch, switchpoints, a switch rod connecting said points and comprising a pair of switch rod members, a connecting rod for con-

trolling the switch, a connecting assembly disposed intermediate the length of said switch rod and connecting said switch rod members together, said assembly having adjusting means to adjust the length of said switch rod, said assembly also having adjusting means for adjusting the relationship between said connecting rod and assembly, and electric insulation between said assembly and said switch rod members.

21. In a railroad switch adjustment, a set of switch rails, a switch rod comprising a set of switch rod members connecting said rails, an adjustment device connecting said rod members, said adjustment device comprising a pair of telescoping members each having a threaded portion and a cylindrical bearing portion, said threaded portions engaging each other to adjust switch rod length, said bearing portions engaging each other to reduce wear on the screw threads.
